COIN-CONTROLLED CREDITING AND
DEBITING APPARATUS FOR VEND-
ING MACHINESMarvin G. Nelsen, Skokie, Ill., assignor to Guard-
ian Electric Manufacturing Co., Chicago, Ill.,
a corporation of Illinois

Application July 9, 1947, Serial No. 759,802.

13 Claims. (Cl. 194—10)

1

This invention relates to coin controlled apparatus and particularly to coin controlled apparatus wherein various articles at different prices or the same price may be selectively vended and the correct change returned in each instance if more money than the price of the merchandise is inserted in the apparatus.

It is an object of the invention to provide coin controlled apparatus for vending several articles of different prices or the same price and deliver correct change when more than the price of the article desired to be purchased is placed in the machine by the vendee.

It is another object of the invention to provide such coin controlled apparatus which is substantially fool-proof and is relatively simple in construction and operation.

It is still another object of the invention to provide coin controlled apparatus of the type specified which is extremely fast in its operation and which delivers the proper article to be vended and the correct change in a very short time.

It is a further object of the invention to prevent the selection and delivery of more than one article at a time in coin controlled apparatus of the above type.

It is still another object of the invention to provide coin controlled apparatus of the above mentioned type which is, for practical purposes, unlimited in the number of different articles it will vend at the same or different prices.

It is a further object of the invention to provide coin controlled apparatus of the above-mentioned type which is practically unlimited in the price or prices of the article to be vended, depending on the denomination of the coins available for use in the apparatus; also to provide ready adjustment of the prices.

It is still a further object of the invention to provide improved coin controlled apparatus and an electrical circuit therefor.

With these and other objects in view, my invention consists in the construction, arrangement and combination of the various parts of my device whereby the objects contemplated are attained, as hereinafter more fully set forth, pointed out in my claims and illustrated in the accompanying drawings, wherein:

Figure 1 is a top plan view of the coin controlled apparatus;

Figure 2 is a view, partially in section, of the rear of the contact plate and movable contactor, taken on line II—II of Figure 1;

Figure 3 is a partial view of the mechanism 55

2

illustrating various coin operated switches, taken on line III—III of Figure 1;

Figure 4 is a partial sectional view of the apparatus, taken on line IV—IV of Figure 1, illustrating a change pay-out solenoid;

Figure 5 is a partial sectional view, taken on line V—V of Figure 1, showing one of the interlock relays;

Figure 6 is a partial sectional view taken on line VI—VI of Figure 1, showing one of the impulse relays;

Figure 7 is a partial sectional view, taken on line VII—VII of Figure 1 showing another impulse relay;

Figure 8 is a partial diagrammatic view of the apparatus including a schematic wiring diagram; and

Figure 9 is a schematic view of the remaining portion of the apparatus and wiring diagram.

Referring specifically to the drawing for a detailed description of the apparatus and circuit, and particularly to Figures 1, 8 and 9, numeral 11 designates a base plate on which are mounted a coin chute, switches and coin rejecting apparatus, generally indicated at 12, and a number of relays, solenoids and contact elements. Specifically, the base plate supports a credit add and subtract device including an add stepper relay 13, a subtract stepper relay 14 and a contact carrying plate 15. The base plate also has mounted thereon a pair of interlock relays 16 and 17, a pair of impulse relays 18 and 19, a plurality of push-button contactors 20a, 20b and 20c, a slow release relay 21, an intermediate relay 22, a plurality of vending solenoids 24a, 24b and 24c, a change pay-out solenoid 25 for releasing nickels or coins of larger denominations, a selenium rectifier 27, if desired, and a push-button locking solenoid 30.

The add relay 13 comprises a coil 28 and an armature 29 pivoted at 31. The armature 29 is provided with an extension 32 which is adapted to engage with teeth 33 of a ratchet wheel 34, which is secured to a shaft 35 journaled in the front of an upright rectangular frame generally indicated at 36. A spring 37 secured to the armature 29 and to a stud 38 tends to bias the armature upwardly and out of engagement with the ratchet wheel 34. A detent 39a is provided for ratchet wheel 34. The add relay 13 is adapted to rotate the ratchet wheel 34 in one direction.

The subtract relay 14 comprises a coil 39 and an armature 41 pivoted at 42. The armature 41 is provided with an extension 43 which is adapt-

ed to engage the teeth 33 of ratchet wheel 34, to rotate the wheel in the opposite direction from the add relay 13. A spring 44 secured to the armature 41 and to the stud 38 tends to bias armature 41 upwardly and out of engagement with teeth 33. A relay operated switch generally indicated at 45 above the subtract coil comprises a pair of fixed contacts 46 and 47 and movable contacts 48 and 50b, which are mounted on an arm snapped between the fixed contacts 46 and 47 by operating member 49 which is moved by armature 41 and a hairpin spring 51, which causes the snap action. Terminals 50 and 50a are provided for one of the fixed contacts 46 and for movable contact 48.

The contactor plate 15 is supported from the front of the rectangular frame 36 from studs 52 and has a large number of contacts 53 arranged in a circle thereon and extending completely through plate 15. The first sixteen contacts are denoted as contacts 53a to 53p inclusive. Also mounted on the plate 15 is a spring contact 54 extending from the front of the plate to a position in back thereof and continuously engaging a contact disc 55 which is mounted on shaft 35 and rotates therewith. This is best shown in Figures 1, 2 and 8. The disc 55 is provided with a projecting arm 56 having a contact button 57 thereon, which engages with one of the contacts 53 depending on the position of ratchet wheel 34 and disc 55.

Referring now to the interlock relays 16 and 17, these are identical in construction, except for the number of contacts on the switches, and are best shown in Figures 1, 5 and 9, only one side view being illustrated since the relays are the same. However, for the sake of clarity of the wiring diagram, Figure 9, the parts of each relay will be given separate numbers and relay 16 may be referred to as "Interlock Relay #2" and relay 17 as "Interlock Relay #1." Relay 16 comprises a pair of coils 58 and 59 mounted on a suitable frame supported on base plate 11. Coil 58 is provided with a pivoted armature 61 normally urged away from the coil by a spring 62. Armature 61 is provided with an upwardly extending switch operating member 63 and with a latch element 64. An armature 65 is associated with coil 59 and is normally held away from coil 59 by a spring 66. The bottom edge of the armature 65 cooperates with latch element 64 to hold armature 61 in its lower position, for a purpose hereinafter explained. Stops 67 and 68 for respective armatures 61 and 65 limit movement thereof away from coils 58 and 59.

The switch operating member 63 operates a switch generally indicated at 69, which comprises two movable switch blades 71 and 72 each having a contact 73 and 74 thereon, respectively. Two relatively fixed spring switch blades 75 and 76 are associated with the respective movable switch blades 71 and 72 and have respective contacts 77 and 78 thereon. Terminals 80 and 81 are associated with the respective movable blades 71 and 72 and terminals 82 and 83 are associated with the two respective fixed blades 75 and 76.

The interlock relay 17 comprises a pair of coils 84 and 85 mounted on a suitable frame 87 supported on base plate 11. Coil 84 is provided with a pivoted armature 88 normally urged away from the coil by a spring 89. Armature 88 is provided with an upwardly extending switch operating member 91 and with a latch element 92. A pivoted armature 93 is associated with coil

85 and is normally held away therefrom by a spring 94. The bottom edge of armature 93 cooperates with the latch element 92 to hold armature 93 in its lower position for a purpose hereinafter described. Stops 95 and 96 for respective armatures 88 and 93 limit movement thereof away from coils 88 and 93.

The switch operating member 91 operates a switch generally indicated at 97 which comprises three movable switch blades 98, 99 and 101 each having a contact 102, 103 and 104 thereon, respectively. Three relatively fixed spring switch blades 105, 106 and 107 are associated with the respective movable switch blades and have respective contacts 108, 109 and 111 thereon. Terminals 112, 113 and 114 are associated with the respective movable switch blades 98, 99 and 101 and terminals 115, 116 and 117 are associated with the respective fixed switch blades, 105, 106 and 107.

Referring specifically to Figures 6 and 7 for a detailed description of the relays 18 and 19, which may be termed a dime and a quarter relay, respectively, numeral 121 designates similar upright spaced plates which are mounted on the base plate 11. The plates 121 have square cut-outs 122 therein bent over to form horizontal supporting flanges 123. L-shaped brackets 124 are supported by angles 125 secured to the plates 121, which L-shaped brackets 124 support respective electromagnets or coils 126 and 127, respectively, for the relays 18 and 19, as well as copper time delay slugs 128 and 129 below each of the coils.

The angles 125 are provided with overhanging portions 131 having apertures therein (not shown) which provide knife edges or pivot points for pivoted armatures 132 and 133 associated with the coils 126 and 127, respectively. The armatures 132 and 133 are provided with grooved extensions 134 and 135, respectively, extending through the aforesaid apertures to retain the armatures in position on their pivot points. Brackets 136 having downwardly turned flanges 137 are secured to angles 125 and limit movement of the armatures 132 and 133. Angles 125 are also provided with lower horizontal extensions 138 and tension springs 139 are connected between the extensions 134 and 135 of armatures 132 and 133 and extensions 138 of angles 125.

Laminations 141 of insulating material are secured to the tops of the brackets 136 and retain fixed contact arms 142 and 143 and a movable arm 144 above coil 126 and fixed contact arms 145 and 146, and movable arm 147 above coil 127. Extensions 148 from brackets 136 extend horizontally above the main portion of armatures 132 and 133 and provide upper limit stops therefor.

The movable arms 144 and 147 extend through slits 149 in insulating pieces 151 attached to the outer ends of the main parts of armatures 132 and 133, as best shown in Figure 1. The movable arms 144 and 147 are formed of spring steel. Flexible fingers 152 and 153 supported from laminations 141 carry contacts 154, 155, and 156, 157 on opposite sides of the respective flexible fingers 152, 153. Hairpin springs 158 are anchored at one end to an intermediate portion of the movable arms 144 and 147, and at the other end to the flexible fingers 152 and 153, respectively. The fixed contact arms 142 and 143 of relay 18 are provided with contacts 159 and 161, respectively, and fixed contact arms 145 and 146 of relay 19 are

provided with contacts 162 and 163, respectively. The hairpin springs 158 provide for snap-acting movement of the movable fingers 152 and 153 after the corresponding armatures 132 and 133 are moved downwardly by energization of coils 126 and 127 and after the armatures are moved upwardly by the tension springs 139 upon de-energization of the coils 126 and 127.

Extensions 164 and 165 secured to the main portion of armatures 132 and 133 extend through lower slits (not shown) in the insulating plates 151 and leaf spring members 166 are secured to the extensions and bias wire pawls 167 and 168 toward ratchet wheels 169 and 171 of relays 18 and 19, respectively. The ratchet wheels 169 and 171 are journaled on shafts 172 and 173, respectively, supported from the upright supporting plates 121. The outer ends of plates 121 are cut and provided with oblique flanges 174. Leaf springs 175 are secured to the plates 121 adjacent the oblique flanges 174 and retain detent balls 176 in engagement with the ratchet wheels 169 and 171 through apertures (not shown) in oblique flanges 174 to add slight resistance to rotation of the ratchet wheels.

Laminations 177 are secured to the underside of flanges 123 and support substantially fixed spring contact arms 178 and 179, carrying respective contacts 181 and 182 for respective relays 18 and 19. The laminations 177 also support movable spring contact arms 183 and 184 having contacts 185 and 186, respectively, thereon. Up to this point, it will be noted that the relays 18 and 19, that is, the dime and quarter impulse relays, are identical.

A wheel, 187, preferably formed of insulating material is mounted on shaft 172 and rotates therewith when ratchet wheel 169 is rotated. Eight equally spaced notches 188 are provided in the periphery of wheel 187. Movable contact arm 183 is provided with an angular extension 189 shaped to fit into the notches 188.

A wheel 191, also preferably formed of insulating material, is mounted on shaft 173 of relay 19 and rotates when ratchet wheel 171 is rotated. Four equally spaced notches 192 are provided in the periphery of wheel 191. Movable contact arm 184 is provided with an angular extension 193 shaped to fit into the notches 192.

Terminals 194, 195 and 196 are provided on the upper fixed switch arm 142, the movable switch arm 144 and the lower fixed switch arm 143, respectively, of relay 18 and terminals 197 and 198 are provided for the coil 126 of relay 18. Likewise, terminals 199, 200 and 201 are associated with the upper fixed contact arm 145, the movable contact arm 147 and the lower fixed contact arm 146, respectively, of relay 19. Terminals 202 and 203 are provided for coil 127 of relay 19.

The slow release relay 21 comprises an upright angle member 204 supported from the base plate 11, which supports a coil 205 provided with a group of time delay copper slugs 206 therebelow. An armature 207 is associated with the coil 205 and is normally biased away from the coil by a tension spring 208, a stop 209 limiting the upward movement of the armature. A switch, generally indicated at 210, is also supported on the angle 204 and comprises a relatively fixed spring contact arm 211 having a contact 211a thereon and a movable spring contact arm 212 having a contact 213 thereon. A plate of insulating material 214 is secured to the armature 207 and the end of the movable contact arm 212 extends therethrough

and is moved up and down upon energization and de-energization of the coil 205. The coil 205 is provided with two terminals 215 and 216 thereon and the switch 210 is provided with two terminals 217 and 218 on the fixed and movable contact arms 211 and 212, respectively.

The intermediate or change pay-out relay 22 comprises an angle member 219 supported on the base plate 11, which angle member in turn supports a coil 221. A pivoted armature 222 is associated with the coil 221 and a tension spring 223 normally retains the armature 222 away from the coil 221. A switch generally indicated at 224 is mounted above the coil 221 and includes two movable contact arms 225 and 225a, having contacts 226 and 226a thereon and relatively fixed spring contact arms 227, 227a and 227b having contacts 228 and 228a thereon. A plate of insulating material 229 is connected to the armature and the ends of the movable contact arms 225 and 225a extend therethrough and are moved up and down upon energization and de-energization of the coil 221. A stop 231 limits the upward movement of the armature 222. The coil 221 is provided with two terminals, 232 and 233, and the switch 224 is provided with terminals 234 and 234a for movable contact arms 225 and 225a, and terminals 235, 235a and 235b for fixed contact arms 227, 227a and 227b. Copper slugs 230 are provided under the coil 221.

The vending or package discharge solenoids 24a, 24b and 24c and the nickel change pay-out solenoid 25 are all identical and comprise coils 246a to 246d, respectively, and movable cores 247a to 247d, respectively. Furthermore, the package or vending solenoids 24a, 24b and 24c are associated with slides 248a, 248b and 248c, which are moved by the cores 247a, 247b and 247c to drop packages 249a, 249b and 249c of the material to be vended through respective package chutes (not shown). On the other hand, the nickel change pay-out solenoid 25, when operated, operates a slide 250 to drop a nickel 251 through a suitable change chute (not shown).

The coin switch and rejection mechanism 12 is of standard design and in the present case includes three switches 254, 255 and 256, which are operated by nickels, dimes and quarters, respectively, dropping through the proper chutes of the coin mechanism 12. The nickel chute is indicated at 257, the dime chute at 258, and the quarter chute at 259. The nickel switch 254 is provided with terminals 261 and 262, the dime switch 255 with terminals 263 and 264, and the quarter switch 256 with terminals 265 and 266. These switches 254, 255 and 256 each contain contacts therein (not shown) which are closed when a coin passes through the respective chutes and operates coin actuated arms 267, 268 and 269 on the respective nickel, dime and quarter switches.

The coin chutes, rejecting mechanism and coin switches are of conventional design and form no part of the present invention per se. The selenium rectifier 27 is also standard equipment and may be used where it is desired to operate the various relays and solenoids on direct current from an alternating current source of supply. Further description of the coin chutes, rejecting mechanism, coin switches, and rectifier is therefore deemed unnecessary.

The push-button contactors 28a, 28b and 28c comprise separate manually operated buttons 271, 272, and 273, respectively, which are preferably of the standard radio push-button type

control, wherein manually pushing in of one button releases the button pushed in before. The push-button locking device 30 comprises a coil 274 and a solenoid 275 having a downward extension 276 adapted to engage with a slideable member 277 to prevent operation or pushing in of a push button other than the one already pushed in, if the coil 274 is energized. The purpose and operation of this construction will be apparent as the description proceeds.

Operating members 278a, 278b and 278c are provided for respective switches generally indicated by numerals 279a, 279b and 279c. The switches are shown in the position that they assume when the respective push buttons are in their outward position, that is, not pushed in.

Referring to switch 279a, it includes four movable contact arms 281, 282, 283 and 284. Movable contact arm 281 has upper and lower contacts 285 and 286 thereon and moves between two relatively fixed spring contact arms 287 and 288, having contacts 289 and 291 thereon. Movable contact arm 282, likewise, has upper and lower contacts 292 and 293 thereon and moves between two fixed spring contact arms 294 and 295, having contacts 296 and 297 thereon. Movable contact arm 283 has a contact 298 thereon, cooperating with a contact 299 on a fixed spring contact arm 301. Movable contact arm 284 has a contact 302 thereon cooperating with a contact 303 on a fixed spring contact arm 304. Terminals 305 to 314 inclusive are provided for the contact arms 287, 281, 288, 294, 282, 295, 283, 301, 284 and 304, respectively. Terminals 316 and 317 are provided on coil 246a of solenoid 24a.

Referring to switch 279b, it also includes four movable contact arms 318, 319, 321, and 322. Movable contact arm 318 has upper and lower contacts 323 and 324 thereon and moves between two relatively fixed spring contact arms 325 and 326, having contacts 327 and 328 thereon. Movable contact arm 319 likewise has upper and lower contacts 329 and 331 thereon and moves between fixed spring contact arms 332 and 333, having contacts 334 and 335 thereon. Movable contact arm 321 has a contact 336 thereon, which cooperates with a contact 337 on a fixed contact arm 338. Movable contact arm 322 has a contact 339 thereon which cooperates with a contact 341 on a fixed contact arm 342. Terminals 343 to 352 inclusive are provided for the contact arms 325, 318, 326, 332, 319, 333, 321, 338, 322, and 342, respectively. Terminals 353 and 354 are provided for the coil 246b of the solenoid 24b.

Referring to switch 279c, it likewise includes four movable contact arms 355, 356, 357 and 358. Movable contact arm 355 has upper and lower contacts 359 and 361 thereon and moves between two fixed spring contact arms 362 and 363 having contacts 364 and 365 thereon. Movable contact arm 356 likewise has contacts 366 and 367 thereon, and moves between two fixed spring contact arms 368 and 369 having contacts 371 and 372 thereon. Movable contact arm 357 has a contact 373, which cooperates with a contact 374 on a fixed spring contact arm 375. Movable contact arm 358 has a contact 376 thereon which cooperates with a contact 377 on fixed spring contact arm 378. Terminals 379 to 388 inclusive are provided for the contact arms 362, 355, 363, 368, 356, 369, 357, 375, 358 and 378, respectively. Terminals 389 and 391 are provided on coil 246c of solenoid 24c.

Operation

Assuming first that the apparatus is arranged to vend 15¢, 35¢ and 60¢ items, terminals 312 and 314 of switch 279a are connected to the second and third contacts 53c and 53d from initial contact 53a on contact member 15 by conductors 400 and 401, respectively. Likewise, terminals 350 and 352 of switch 279b are connected to the sixth and seventh contacts 53g and 53h from initial contact 53a by conductors 402 and 403, respectively, and terminals 386 and 388 of switch 279c are connected to the eleventh and twelfth contacts 53-l and 53-m from initial contact 53a by conductors 404 and 405. Preferably, the coin responsive switches 254, 255 and 256 are operated by nickels, dimes or quarters, respectively, and the impulse relays 18 and 19 by dimes and quarters. It will be obvious, however, as the description proceeds, that the switch terminals 312-314, 350-352 and 386-388 may be connected to any respective adjacent contacts 53 to change the price of the articles or items to be vended, and that the coin responsive switches 254, 255 and 256 may be operated by coins of other denominations, such as dimes, quarters and half dollars, and the impulse relays 18 and 19 by quarters and half dollars.

Assuming now that the purchaser wishes to purchase the 15¢ item, the push-button 271 is pushed in and if it is not already in, it releases the other two push-buttons, and moves the switches 279b and 279c to the position shown in Figure 9, with contacts 323-327 and 329-334 of switch 279b closed, contacts 359-364 and 366-371 of switch 279c closed, and the remaining contacts of these two switches open. However, on switch 279a, the 15¢ switch, contacts 285-289 and contacts 292-296 are opened, and contacts 286-291, 293-297, 298-299 and 302-303 are closed.

Assuming that the purchaser then places the exact amount in coins in the coin chute, that is, a nickel and a dime or three nickels, the following circuits are established and operations occur.

When a nickel is inserted in the coin chute, the contacts of the nickel responsive switch 254 are closed, and a D. C. circuit is established from the positive side of line D1 through terminal 261, conductor 406, momentarily closed contacts of nickel switch 254, conductor 407, terminal 262, conductor 408, terminal 199, conductor 409, terminal 194, conductor 411, through the add coil 28 and back to line D2 through conductor 412, thus energizing the add coil 28 once and immediately de-energizing it when the nickel passes the nickel switch 254. The contact arm 56 is, therefore, moved one step by the mechanism described to engage contact 53b and disengage from initial contact 53a.

It will be noted that the initial movement of the disc 55 carrying contact arm 56 mechanically closes contacts 413 and 414 mounted on switch arms 415 and 416, respectively, because the end of spring switch arm 415 is released by a projection 417 on disc 55 moving away from switch arm 415. The contacts 413-414, therefore, remain closed until the contact arm 56 is again returned to the initial contact 53a and end of switch arm 415 is forced to the open position. Terminals 418 and 419 are provided for switch arms 415 and 416.

An A. C. circuit is, therefore, established from line L1, through a conductor 421 connected to terminal 419, closed contacts 413-414, terminal 75 418, conductor 423, through A. C. coil 30 and

back to line L2 through a conductor 424. The push-button lock solenoid 30 is, therefore, energized and locks the remaining push-buttons and prevents them from being pushed in and thus prevents closure of contacts 324—328 and 331—335 of switch 279b and contacts 361—365 and 367—372 of switch 279c. It is, therefore, impossible to energize article dispensing solenoids 24b and 24c and accidental or intentional delivery of the articles, whose delivery is controlled by those solenoids, is prevented. Obviously, the push-button lock solenoid 30 remains energized until a vending operation is completed and the disc 55 and contact arm 56 returned to their initial position. The same operation takes place regardless of the denomination of the coin first inserted since, as will be apparent as the description proceeds, the credit coil 28 is immediately energized as soon as a coin is deposited, and contacts 413—414 are mechanically closed to energize push button locking solenoid 30.

Another D. C. circuit is established when the nickel switch 254 is operated, to energize the slow release or circuit locking relay coil 205, although no useful function is effected by such energization. This circuit follows the D. C. circuit before described, from line D1 through conductor 411, and then branches through a conductor 425 to terminal 215 of slow release coil 205, through coil 205, terminal 216 and back to line D2 through conductor 426. Coil 205 is thus energized and contacts 211a—213 are opened. However, unless other coins are quickly deposited, coil 205 is deenergized and contacts 211a—213 are closed. Opening and closing of contacts 211a—213, however, does not establish or break any circuits at this time, except to isolate a conductor 427 between terminal 217 of the slow release relay 21 and terminal 115 of interlock relay switch 97, since contacts 102—108 of that switch are open.

Assume now that another nickel is inserted to operate nickel switch 254, the same sequence of operations are followed and circuits established as described above, and contact arm 56 is moved to the second contact 53c from initial contact 53a. No circuits are established except that the conductor 400 extending between contact 53c and terminal 312 of switch 279a and terminal 113 of switch 97 of interlock relay 17, are both connected to A. C. line L1 through conductor 421, disc 55 and contact arm 56. It is noted at this time that contacts 298—299 of switch 279a are closed and contacts 103—109 of switch 97 are open.

Assume now that another nickel is inserted to operate the nickel switch 254, again the same circuits are established and operations are followed as described above, and the contact arm 56 is stepped to the third contact 53d from initial contact 53a. The following additional circuits are then established.

An A. C. circuit is established from line L1, through conductor 421, disc 55, movable contact arm 56, contact 53d, conductor 401, closed contacts 302—303 of switch 279a, a conductor 429, coil 84 of interlock relay 17 and back to line L2 through conductor 431. The coil 84 is thus energized and its armature 88 is locked in its downward position by the latch 92. Contacts 102—108 and 103—109 of switch 97 are, therefore, closed.

Closure of contacts 102—108 establish the following circuits. First, a circuit is established from D. C. line D1, through a conductor 432,

closed contacts 211a—213 (which are closed as soon as all coins are credited), conductor 421 and closed contacts 102—108.

A branch circuit from terminal 112 of interlock switch 97 is established through a conductor 437 through closed contacts 226a—228a, through a conductor 438, through subtract coil 39 of the stepper means and back to line D2 through a conductor 439. The switch arm 56 is, therefore, moved from contact 53d to contact 53c and subtract switch 45 is immediately operated by energization of the subtract coil 39, and the merchandise dispensing solenoid 24a is operated to dispense a 15¢ article through energization of coil 246a as follows: One branch circuit then is established from terminal 112 of switch 97, through a conductor 434 to terminal 50a of stepper relay switch 45, through closed contacts 47—50b, through terminal 50, conductor 435, change payout relay coil 221 and back to line D2 through a conductor 436, thus energizing change payout relay coil 221. Contacts 226a—228a are opened and contacts 226—228 are closed each time the coil 221 is energized. Each time coil 221 is de-energized contacts 226a, 228a are returned to closed position and contacts 226, 228 are returned to open position.

Operation of the change payout relay and closure of contacts 226—228 establishes the following A. C. circuit, as soon as contact arm 56 reaches contact 53c: from line L1, through conductor 421, disc 55, contact arm 56, conductor 400, closed contacts 298—299 of switch 279a, through a conductor 441, through closed contacts 103—109 of interlock switch 97, through a conductor 442, a conductor 443, closed contacts 286—291 of switch 279a, through a conductor 444, 15¢ merchandise payout coil 246a, a conductor 445, closed contacts 293—297 of switch 279a, through a conductor 446, through closed contacts 329—334 of switch 279b, a conductor 447, closed contacts 366—371 of switch 279c and through a conductor 448 to line L2. The 15¢ coil 246a is thereby energized to deliver a 15¢ article.

Opening of the contacts 47—50b of subtract switch 45 breaks the circuit through the change payout relay coil 221, starting from line D1 and conductor 432 and ending at conductor 436 and line D2. The change payout relay coil 221 is thereby deenergized. Contacts 226a—228a are then closed, and subtract coil 39 is reenergized, thus closing contacts 47—50b, again energizing change payout relay coil 221 and again opening contacts 226a—228a. This alternating operation continues as long as contacts 102—108 of switch 97 are latched closed, which condition exists until movable contact arm 56 reaches the initial contact 53a again, arm 56 being stepped back one contact each time the subtract coil 39 is energized, as hereinbefore described.

The change payout switch 224 is first operated when the movable contact arm 56 is moved from the third contact 53d to the second contact 53c and at that time the coil 58 of interlock relay 16 is operated to open contacts 73—77 and close contacts 74—78 of switch 69. As long as contacts 73—77 are open, energization of the change payout solenoid 246d is impossible, even though contacts 226—228 of the change payout switch 224 are being alternately opened and closed.

The coil 58 operates more rapidly than the coil 221, so as to open contacts 73, 77 before contacts 226, 228 are closed, thus opening the circuit to the change payout solenoid 246d.

When the movable contact arm 56 reaches initial contact 53a, the following circuits are established to energize reset coils 59 and 85 of interlock relays 16 and 17 to reset the contacts of switches 69 and 97 to the positions shown in Figures 9 and 10, thus stopping operation of the add and subtract stepper means, since contacts 102-108 are opened. The A. C. circuits which are established are from conductor 421, the disc 55, contact arm 56, contact 53a, through a conductor 449 to terminal 114, closed contacts 104-111 of switch 97, through a conductor 451, reset coil 85 and back to line L2 through conductors 452 and 431, thus energizing reset coil 85. A simultaneous branch circuit is established from terminal 114 of interlock switch 97, through a conductor 453, through closed contacts 74-78 of interlock switch 69, through a conductor 454, reset coil 59, a conductor 455 and back to line L2 through conductor 440. Immediately upon energization of the reset coils 59 and 85, the latches 64 and 92 are released and contacts 74-78 of interlock switch 69 and contacts 104-111 of interlock switch 97 are opened, thus deenergizing the reset coils 59 and 85. If continuous duty coils 59 and 85 are used, contacts 74-78 and 104-111 are not essential. Obviously, contacts 73-77 of interlock switch 69 are closed and contacts 102-108 and 103-109 of interlock switch 97 are opened at this time, thus conditioning the circuit and apparatus for another vending operation.

Assume now that more than sufficient coins are inserted for purchasing a 15¢ article, for example, two dimes or a quarter. Some coin chutes automatically reject excess coins—for example, if three dimes were inserted for purchasing a 15¢ article, the third dime would not operate the dime switch, but would be immediately returned. Such coin chutes are well known and no further description is believed to be necessary.

If two dimes are inserted, the 10¢ switch 255 is operated twice very quickly, and four credits are set up, since the add or credit coil 13 of the stepper is energized four times in the following manner, and the following sequence of operations occur.

A D. C. circuit is established from line D1, through terminal 261, conductor 456, terminal 266, conductor 457, terminal 264, conductor 458, closed contacts (not shown) of 10¢ switch 255, a conductor 459, terminal 193, through conductor 461, through coil 126 of the 10¢ impulse relay 18, through conductors 462 to terminal 204 and back to line D2. The coil 126 is thus energized and wheel 187 turned one step, in a manner hereinbefore described. The projection 189 is, therefore, raised from notch 188 of wheel 187 and contacts 181-185 are closed. Energization of coil 126 also opens contacts 155-161 and closes contacts 154-159. Closing of contacts 154-159 establishes a D. C. circuit to energize the add coil 28 from line D1, through conductors 463 and 464, closed contacts 181-185 of 10¢ switch 18, a conductor 465, closed contacts 154-159 of 10¢ switch 18, conductor 411, add coil 28 and back to line D2, through conductor 412. Contact arm 56 is, therefore, moved one step to contact 53b.

Opening of contacts 155-161 of 10¢ impulse relay 18 deenergizes its coil 126 and contacts 154-159 are, therefore, opened and contacts 155-161 are closed. Coil 126 is then reenergized and contacts 154-159 are closed and contacts 155-161 are opened, thereby transmitting a second impulse to the add coil 28, moving contact

arm 56 to the next contact 53c and again deenergizing the 10¢ relay coil 126. The same sequence of operations follows, except that the third time the coil 126 is energized, the wheel 187 is moved so that the projection 189 drops into the next notch 188 and contacts 181-185 are opened so that no impulse may be transmitted to the add coil 28 and operation of the 10¢ relay stops. Obviously, however, the second dime effects the same operation of the 10¢ relay 18 and as a result, the contact arm 56 is moved four contacts in all to contact 53e.

During the rapid operation of the add coil 28, the slow release coil 21 has had four fairly rapid impulses transmitted to it through conductor 425, and because of the characteristics imparted thereto by the copper slugs 206, the contacts 211-213 thereof remain open until all the coins are credited. It is, therefore, impossible for the subtract coil 39 or the change payout coil 221 to be energized until contacts 211-213 close. While relays 126 and 127 are of the slow release type, they pulse with sufficient rapidity to maintain slow release coil 21 energized, the copper slugs 206 being rather heavy as compared with the slugs 128, 129 associated with relays 126, 127, respectively.

However, as the contact arm 56 passes the third contact 53d, the interlock relay coil 84 is energized in the manner hereinbefore described and contacts 102-108, 103-109 and 104-111 of switch 97 are closed. It is also to be noted that contacts 73-77 of switch 69 of interlock relay 16 are closed at this time, and contacts 74-78 thereof are open.

As soon as contacts 211-213 are closed, the change payout relay coil 221 and the subtract coil 39 are alternately energized and deenergized in the manner hereinbefore described. As the movable contact 56 travels from contact 53e to 53d, contacts 226-228 of change payout relay switch 224 are closed, and since contacts 73-77 of interlock relay 16 are closed, the following A. C. circuit is established to energize the change payout solenoid 246d to pay out one nickel. From line D1, through a conductor 466, closed contacts 73-77 of interlock relay 16, a conductor 467, momentarily closed contacts 226-228 of change payout switch 224, through conductor 450 to change payout solenoid 246d and to line L2 through a conductor 468, thus effecting operation of the nickel slide and delivery of one nickel.

Upon the next energization of the subtract coil 39, the contact arm 56 is moved from the third contact 53d to the second contact 53c. The interlock relay coil 58 is, therefore, energized in a manner heretofore described and contacts 73-77 of relay 16 are opened and contacts 74-78 closed. Even though the contacts 226-228 of change payout switch 224 are again closed, the change payout solenoid 246d cannot again be energized. Also at this time, the merchandise solenoid 246a is energized to deliver a 15¢ article, in a manner heretofore described. The subtract coil is alternately energized and deenergized until the movable contact arm 56 reengages with the initial contact 53a, whereupon the reset coils 59 and 85 of the interlock relays 16 and 17 are energized to release the latches and condition the circuit for another vending operation.

Assume now that a quarter is utilized to purchase a 15¢ article. The quarter momentarily closes contacts (not shown) of the quarter impulse switch 256 and the following circuits are established. From D. C. line D1, through con-

ductor 456, terminal 266, conductor 469, closed contacts of the quarter switch 255, conductors 471, 472 and 473, through coil 127 of the quarter impulse switch 19, and back to line D2. Coil 127 is, therefore, energized and rotates wheel 191 one step, thereby forcing the projection 193 out of notch 192 and closing contacts 182—186. A circuit is then established from line D1, through conductor 463, closed contacts 182—186, conductor 474, through contacts 156—162 which have been closed upon energization of coil 127 through the conductors 409 and 411, through the add coil 28 and conductor 412 back to line D2, thus energizing the add coil 28. The movable contact arm 56 is, therefore, moved one step to the second contact 53b and contacts 413—414 are closed to operate the push-button lock solenoid 30, through the circuit heretofore described.

Contacts 157—163 of the quarter impulse switch are opened upon energization of the coil 127 and the coil is thereby immediately deenergized so that contacts 157—163 are closed and contacts 156—162 are opened, thus deenergizing the add coil 28 and again energizing the coil 127. The contacts 157, 163 are again immediately opened, contacts 156—162 are closed, wheel 191 is turned another step and contact arm 56 is moved to the third contact 53c. However, no circuits are established at this time.

The coil 127 of the quarter relay 19 is energized six times, and on the sixth energization, the projection 193 drops into the next notch 192, thus opening contacts 182—186. No circuit may, therefore, be established through closed contacts 156—162 with the result that the add coil 28 receives only five impulses. The movable contact arm 56, therefore, is moved to the contact 53f. The impulse relay 19 thereupon stops its operation.

When the contact arm 56 contacts the third contact 53d, as the add coil is operating, the previously described circuit is established to energize the coil 84 of interlock relay 17 to latch closed contacts 102—108, 103—109 and 104—111 of switch 97. However, as long as the relay 19 is operating, the slow release or circuit locking relay 21 maintains the contacts 211a—213 thereof open so that neither the change pay-out coil 221 nor the subtract coil 39 may be energized. However, as soon as the 25¢ impulse relay 19 ceases to operate, the coil 205 of the circuit locking relay is de-energized and contacts 211a—213 close.

As soon as contacts 211a—213 close, the previously described circuit to alternately energize and de-energize, the change pay-out relay coil 221 and the subtract coil 39 are established and each time the contacts 226—228 of the change pay-out relay are closed, the change pay-out coil 246d is energized to deliver one nickel. Furthermore, the contact arm 56 is successively stepped back from contact 53f to contact 53a. A nickel is, therefore, delivered when contact 56 moves to contact 53e and a second nickel is delivered when contact arm 56 is moved from contact 53e to contact 53d. When the contact arm 56 is moved to contact 53c, however, the coil 58 of the interlock relay 16 is energized to open contacts 73—77 and prevent further energization of the change pay-out coil 246d. Energization of coil 58 also closes contacts 74—78 in the manner hereinbefore described.

Furthermore, the circuit heretofore described is established to energize the merchandise delivery coil 246a to deliver a 15¢ article. It will be obvious, therefore, that 10¢ in change and the

15¢ article will be delivered when a quarter is dropped in the coin chute.

When the contact arm 56 reaches the contact 53a, the release magnet coils 59 and 85 of interlock relays 16 and 17 are energized to unlatch the relays and position the contacts in the manner shown in Figures 9 and 10. The release magnet coils 59 and 85 are therefore de-energized, the contacts 413—414 are opened to de-energize the push-button lock solenoid 30, and the apparatus and circuits are conditioned for another vending operation.

Assume now that a 35¢ item is desired, it is necessary to insert at least 35¢ in the coin chutes 15 in coins of any denomination, and the nickel, dime, and quarter switches will establish the circuits heretofore described to move the contact arm 56 into successive engagement with the various contacts and to hold open the slow release relay contacts 211—213 until all coins are credited.

However, prior to inserting coins, the 35¢ push-button 272 is pushed in and the 15¢ push-button switch 279a and the 60¢ push-button switch 279c have their contacts positioned in the manner shown in Figure 10. However, the 35¢ push-button switch 279 has contacts 323—327 opened, contacts 324—328 closed, contacts 329—334 opened, and contacts 331—335, 336—337 and 339—341 closed. It is obvious therefore that no circuits will be established when the contact arm passes the contacts 53c, 53d because contacts 298—299 and 302—303 of the 15¢ switch 279a are open.

When the contact arm 56 reaches the seventh contact 53h from the initial contact 53a, the interlock relay 17 has coil 84 thereof energized, since a circuit is established from line L1 through conductor 421, contact arm 56, contact 53b, conductor 403, through closed contacts 339—341 of push-button solenoid switch 279b, through a conductor 475 to terminal 313 of push-button switch 279a, through conductor 429, coil 84 of interlock relay 17, and back to line L2 through conductor 431, thus energizing the coil 84. As described above, contacts 102—108, 103—109 and 104—111 are thereby closed.

If exactly 35¢ has been inserted in the machine, the circuit-locking relay is de-energized and contacts 211a—213 thereof are closed. The change pay-out relay 22 and the subtract coil 39 are, therefore, alternately energized and when contact arm 56 reaches the sixth contact 53g, the coil 58 of the interlock relay 16 is energized through the following circuit: from line L1 through conductor 421, contact arm 56, contact 53g, conductor 402, through closed contacts 336—337 of push-button switch 279b, conductor 476 to terminal 311 of push-button switch 279a, conductor 441, closed contacts 103—109 of interlock relay switch 97, conductor 442, coil 58 of interlock relay 16 and back to line L2 through conductor 440, thus energizing coil 58, opening contacts 73—77 and closing contacts 74—78 thereof. The change pay-out coil 246d therefore cannot be energized, since contacts 73—77 are open, even though the contacts 226—228 of the change pay-out switch 224 are alternately opened and closed until the contact arm 56 again reaches initial contact 53a. A second circuit is established to operate the 35¢ merchandise coil 246b, as follows:

From line L1 through conductor 421, contact 53g, conductor 402, closed contacts 336—337, through conductor 476 to terminal 311 of switch 279a through conductor 441, closed contacts 103—109 of interlock switch 97, through conductor

442 and 443 through closed contacts 285—289 of push-button switch 279a, through a conductor 477, through closed contacts 324—328 of push-button switch 279b, through a conductor 478, through merchandise coil 246b, through a conductor 479, closed contacts 331—335 of push-button switch 279b, conductor 441, closed contacts 366—371 of push-button switch 279c and back to line L2 through conductor 448. The 35¢ solenoid coil 246b is, therefore, energized and a 10 35¢ item is vended.

If more than 35¢ is inserted in the apparatus—for example, two quarters—the contact arm 56 will move to the tenth contact 53k. Thereafter, as the subtract coil 39 is successively energized, the contact arm will move to the contacts 53j, 53i and 53h and the nickel change coil 246d will be energized three times to return three nickels in the manner described with respect to the 15¢ article vending operation. When the contact arm reaches the sixth contact 53g, energization of coil 58 of interlock relay 16 prevents any further energization of the change pay-out solenoid 246d. When the contact arm is stepped back to the initial contact 53a, the push-button lock solenoid contacts 413—414 are opened, the release magnet coils 59 and 85 of the interlock release 16 and 17 are energized to position the contacts of the interlock relays, as shown in the wiring diagram and to condition the circuit and apparatus for another vending operation.

Assume now that it is desired to purchase the 60¢ item, the push-button 273 is pushed in, thus positioning the 15¢ and 35¢ push-button switches 279a and 279b in the position shown in the wiring diagram. However, the 60¢ push-button switch 279c has contacts 359—364 opened, contacts 361—365 closed, contacts 366—371 opened and contacts 367—372, 373—374 and contacts 376—377 closed.

If exactly 60¢ is inserted in the apparatus in nickels, dimes or quarters, the coins will be credited in the manner described heretofore and the contact arm 56 will be moved to the twelfth contact 53m. At the time that the last coin is being credited, the contacts 211a—213 of the slow release relay 21 are open, since the coil 205 thereof is energized through the circuit heretofore described. Furthermore, since contacts 298—299 and 302—303 of push-button switch 279a are open, no circuits are established as the contact arm 56 passes the second and third contacts 53c and 53d. Likewise, since contacts 336—337 and 339—341 of push-button switch 279b are open, no circuits are established as the contact arm 56 passes the sixth and seventh contacts 53g and 53b.

When the contact arm 56 reaches the contact 53m, however, a circuit is established from line L1 through conductor 421, contact arm 56, terminal 53m, conductor 405, closed contacts 316—317 of push-button switch 279c, through a conductor 450 to terminal 351 of push-button switch 279b through conductor 475 to terminal 313 of push-button switch 279a, through conductor 429, coil 84 of interlock relay 17 and back to line L2 through conductor 431, thus energizing coil 84. Contacts 102—108, 103—109 and 104—111 of switch 97 are, therefore, closed.

As soon as all the coins are credited, the contacts 211a—213 of the slow release relay 21 close, the change payout relay coil 221 and the subtract coil 39 are alternately energized, as described above, thus moving the contact arm 56 toward the initial contact 53a. As the contact

5 16 arm 56 moves from contact 53m to 53—1, the following circuits are established.

From line L1 through conductor 421, contact arm 56, contact 53L, conductor 404, through closed contacts 373—374 of push-button switch 279c, through a conductor 481 to terminal 349 of push-button switch 279b through conductor 476 to terminal 311 of push-button switch 279a, through conductor 441, closed contacts 103—109 of interlock relay switch 97, through conductor 442. The circuit then branches—one branch passing through coil 58 of interlock relay 16 and conductor 446 back to line L2, thus energizing coil 58. Contacts 73—77 of interlock relay switch 69 are therefore opened and the change pay-out coil 246d cannot be energized, even though contacts 226—228 of the change pay-out switch 224 alternately open and close.

Another branch of the circuit passes from conductor 442 through conductor 443, closed contacts 285—289 of push-button switch 279a, through conductor 477, closed contacts 323—327 of push-button switch 279b, a conductor 482, closed contacts 361, 365 of push-button switch 279c, a conductor 483, coil 246c of the 60¢ pay-out solenoid 24c, a conductor 484, closed contacts 367—372 of push-button switch 279c and back to line L2 through a conductor 448. Coil 246c is therefore energized and a 60¢ item is vended.

Assume now that more than 60¢ is inserted in the machine—for example, 75¢. The 75¢ will be credited in the manner described and the contact arm 56 will move to the fifteenth contact 53p from the initial contact 53a. As soon as all the coins have been credited, the contacts 211a—213 of the slow release relay 21 close and the change pay-out relay coil 221 and the subtract coil 39 are alternately energized. Contact arm 56 is therefore moved successively to contacts 53o, 53n and 53m and contacts 226—228 of the change pay-out relay switch 224 are closed three times, thus energizing the change pay-out coil 246d three times and delivering three nickels in change. Thereafter, the interlock relay 16 operates to open the contacts 73—77 of switch 69 thereof and the change pay-out coil 246d cannot thereafter be energized, even though contacts 226—228 of the change pay-out relay switch 224 open and close.

From the foregoing, it will be apparent that 50 I have provided apparatus and circuits for vending a plurality of different priced articles and for delivering the proper change if more coins are inserted in the apparatus than the article vended costs. Furthermore, the apparatus is practically 55 unlimited in the number of articles which may be vended and is only limited insofar as the cost of the articles by the denominations of the coins which are available and the number of contacts placed on the contactor 15. The device is also capable of dispensing more than one article at the same price, as this depends entirely upon which of the push-buttons is selected and the connections thereto from the contactor 15.

Furthermore, as soon as all the coins are 60 inserted, the apparatus immediately pays out the change due, if any, and thereafter immediately delivers the merchandise. These operations are performed before the contact arm 56 is returned all the way to its initial position. In addition, the relays and other apparatus described operate 65 very rapidly so that the customer is assured of the proper change and the article within a very short time after the article is selected and the coins deposited.

Some changes may be made in the construction and arrangement of the parts of my coin controlled apparatus without departing from the real spirit and purpose of my invention, and it is my intention to cover by my claims any modified forms of structure or use of mechanical equivalents which may be reasonably included within their scope without sacrificing any of the advantages thereof.

I claim as my invention:

1. Apparatus for vending a plurality of different priced articles one at a time, comprising a plurality of coin responsive switch means for coins of different denominations, an electrical add and subtract stepper means for crediting and debiting units represented by said coins in response to operation of one or more of said switch means, a set of spaced contacts, contact means movable by said stepper means for an initial contact to subsequent contacts and then back to said initial contact, a plurality of circuits connected to predetermined spaced contacts, means for selectively affording energization of certain of said circuits depending on the article the vendee desires to purchase, an impulse means responsive to one of said coin responsive means which is operated by a coin of a larger denomination than that corresponding to a single unit, means for translating the impulses from said impulse means to said stepper means to credit the proper number of units, a plurality of article delivery means, means for operating a predetermined one of said article delivery means incident to sufficient coins having been inserted to cause said add stepper means to move said movable contact means a sufficient distance to pass one of said set of subsequent contacts, engage another thereof and return to one of said spaced contacts to establish the circuit previously selected, means energized incident to engagement of said movable contact means with said another of said set of subsequent contacts for then energizing said subtract stepper means to return said movable contact means to said initial contact, said energized means including an interlock relay for preparing a circuit which is completed by return of said movable contact means to the first of said set of spaced contacts, and an instantaneous circuit established by engagement of said movable contact with said initial contact to reset said interlock relay and thereby condition said apparatus for another vending operation and to break said instantaneous circuit.

2. Apparatus for vending a plurality of different priced articles, one at a time, and making proper change with each article if more than the price thereof is inserted in the apparatus, said apparatus comprising a plurality of coin responsive means for coins of a single unit and of a larger than single unit denominations, an add and subtract means for crediting and debiting units represented by said coins, a set of spaced contacts, interlock relay means, contact means movable by said add and subtract means from an initial contact to subsequent contacts and then back to said initial contact, a circuit connected to each of two spaced contacts for each priced article, means for selectively affording energization of two of said circuits depending on the article the vendee desires to purchase, said last means comprising a plurality of manually operated switches, a locking solenoid for preventing operation of said switches after coins have been inserted in said apparatus and before delivery of an article, an impulse means responsive to one of said coin responsive means which is operated by a coin of larger de-

nomination than that corresponding to a single unit, means for translating the impulses from said impulse means to said add and subtract means to credit the proper number of units, said add and subtract means also being energized in response to operation of a coin responsive means corresponding to a single unit denomination, a plurality of article delivery means, electrically operated means for operating a predetermined one of said article delivery means in response to operation of said coin responsive means and said interlock relay means incident to sufficient coins having been inserted to cause said add and subtract means to move said movable contact means a sufficient distance to pass a first contact to establish one of said circuits previously selected and engage or pass the second contact to prepare said second circuit previously selected and return to the first of the pair of selected contacts, and electrically operated means including said interlock relay means for energizing said add and subtract means to return said movable contact means to said initial contact after the add and subtract means has credited units corresponding to all of the coins utilized.

3. Apparatus for vending a plurality of different priced articles, one at a time, comprising a plurality of coin responsive means for coins of a single unit and of a larger than single unit denominations, add and subtract means for crediting and debiting units represented by said coins, a plurality of spaced contacts, contact means movable by said add and subtract means from an initial contact to subsequent contacts and then back to said initial contact, a plurality of circuits connected to predetermined spaced contacts, an interlock relay disposed in at least one of said circuits and including a switch, means for selectively affording energization of certain of said circuits depending on the article the vendee desires to purchase, an impulse means responsive to one of said coin responsive means, which is operated by a coin of larger denomination than that corresponding to a single unit, means for translating the impulses from said impulse means to said add and subtract means to credit the proper number of units, said add and subtract means also being energized in response to operation of a coin responsive means corresponding to a single unit denomination, a plurality of article delivery means, electrical operating means for operating the article delivery means selected incident to sufficient coins having been inserted to cause said add and subtract means to move said movable contact means a sufficient distance to engage a predetermined one of said contacts to establish the circuit previously selected and a second contact following said last mentioned contact, said interlock switch controlling the circuit to said electrical operating means, said interlock relay being energized upon engagement of the movable contact means with said one of said contacts to operate said interlock switch and energize said electrical operating means when said movable contact means returns to a contact which it engaged prior to said one of said contacts as said add means was operated, and means for energizing said add and subtract means to return said movable contact means to said initial contact after said movable contact means engages said one of said contacts.

4. Apparatus for vending a plurality of different priced articles, one at a time, comprising a plurality of coin responsive means for coins of a single unit and of a larger than single unit de-

nominations, add and subtract means for crediting and debiting units represented by said coins, a plurality of spaced contacts, contact means movable by said add and subtract means from said initial contact to subsequent contacts and then back to said initial contact, a plurality of circuits connected to predetermined spaced contacts, an interlock relay disposed in at least one of said circuits and including a switch, means for selectively affording energization of certain of said circuits depending on the article the vendee desires to purchase, an impulse means responsive to one of said coin responsive means, which is operated by a coin of larger denomination than that corresponding to a single unit, means for translating the impulses from said impulse means to said add and subtract means to credit the proper number of units, said add and subtract means also being energized in response to operation of a coin responsive means corresponding to a single unit denomination, a plurality of article delivery means, electrical operating means for operating the article delivery means selected incident to sufficient coins having been inserted to cause said add and subtract means to move said movable contact means a sufficient distance to engage a predetermined one of said contacts to establish the circuit previously selected and a second contact following said last mentioned contact, said interlock switch controlling the circuit to said electrical operating means, said interlock relay being energized upon engagement of the movable contact means with said one of said contacts to operate said interlock switch and energize said electrical operating means when said movable contact means returns to a contact which it engaged prior to said one of said contacts as said add means was operated, said interlock means being latched into one position upon initial energization thereof, means for energizing the subtract means for moving said movable contact means back to said initial contact, and means for unlatching the interlock means when the movable contact means returns to said initial contact.

5. Apparatus for vending a plurality of different priced articles, one at a time, comprising a plurality of coin responsive means for coins of a single unit and of a larger than single unit denominations, add and subtract means for crediting and debiting units represented by said coins, an initial contact and first and second spaced contacts, contact means movable by said add and subtract means from said initial contact to subsequent contacts and then back to said initial contact, a plurality of circuits connected to predetermined spaced contacts, a pair of interlock relays connected in circuits controlled by separate spaced contacts, means for selectively affording energization of at least two of said circuits, each including one interlock relay, depending on the article the vendee desires to purchase, an impulse means responsive to one of said coin responsive means which is operated by a coin of larger denomination than that corresponding to a single unit, means for translating the impulses from said impulse means to said add and subtract means to credit the proper number of units, said add and subtract means also being energized in response to operation of a coin responsive means corresponding to a single unit denomination, a plurality of article delivery means, means for operating a predetermined one of said article delivery means when sufficient coins have been inserted to cause said add and subtract means to move said movable contact means a sufficient dis-

tance to engage said second contact after having engaged the first one to establish a circuit for one of said interlock relays previously selected, said interlock relays including latching means operable upon initial energization thereof, the other of said interlock relays being initially energized upon the movable contact means engaging said first contact depending upon the circuit selected after having engaged said second contact, and means for energizing said add and subtract means after the movable contact means has engaged said second contact to return said movable contact means to said initial contact.

6. Apparatus for vending a plurality of different priced articles, one at a time, comprising a plurality of coin responsive means for coins of a single unit and of a larger than single unit denominations, add and subtract means for crediting and debiting units represented by said coins, first and second spaced contacts, contact means movable by said add and subtract means from an initial contact to subsequent contacts and then back to said initial contact, a plurality of circuits connected to predetermined spaced contacts, a pair of interlock relays connected in circuits controlled by separate spaced contacts, means for selectively affording energization of at least two of said circuits, each circuit including one of said interlock relays, depending on the article the vendee desires to purchase, an impulse means responsive to one of said coin responsive means which is operated by a coin of larger denomination than that corresponding to a single unit, means for translating the impulses from said impulse means to said add and subtract means to credit the proper number of units, said add and subtract means also being energized in response to operation of a coin responsive means corresponding to a single unit denomination, a plurality of article delivery means, means for operating a predetermined one of said article delivery means in response to operation of said coin responsive means when sufficient coins have been inserted to cause said add and subtract means to move said movable contact means a sufficient distance to engage said second contact after having engaged the first one to establish a circuit previously selected for one of said interlock relays, said interlock relays including latching means operable upon initial energization thereof, the other of said interlock relays being initially energized upon the movable contact means engaging said first contact on returning thereto after engagement with said second contact depending upon the circuit selected, means for energizing said add and subtract means to return said movable contact means to said initial contact, and means for unlatching both upon the circuit selected after having engaged said second contact, means for energizing said add and subtract means to return said movable contact means to said initial contact, and means for unlatching both of said interlock relays when said movable contact means reaches said initial contact to condition the circuit for another vending operation.

7. Apparatus for vending a plurality of different priced articles, one at a time, comprising a plurality of coin responsive means for coins of a single unit and of a larger than single unit denominations, an add and subtract means for crediting and debiting units represented by said coins, a source of electrical power, a set of spaced contacts, contact means movable by said add and subtract means from an initial contact to subsequent contacts and then back to said initial

21

contact, a plurality of circuits connected to predetermined spaced contacts, means for selectively affording energization of certain of said circuits depending on the article the vendee desires to purchase, an impulse means responsive to one of said coin responsive means which is operated by a coin of a larger denomination than that corresponding to a single unit, means for translating the impulses from said impulse means to said add and subtract means to credit the proper number of units, said add and subtract means also being energized in response to operation of a coin responsive means corresponding to a single unit denomination, a slow release relay including contacts thereon which are normally closed, and which are held in the open position during the time impulses are being translated to credit the proper number of units, a plurality of article delivery means, electrical means for operating the selected article delivery means in response to operation of said coin responsive means when sufficient coins have been inserted to cause said add and subtract means to move said movable contact means a sufficient distance to engage a contact to establish the circuit previously selected, relay means then energized for preparing a circuit to one of said spaced contacts for said article delivery means which circuit is completed by return of said movable contact means to said last mentioned contact, said slow release contacts being disposed in a circuit between said source of power and said subtract means so that when open the subtract means is rendered ineffective, and means for energizing said add and subtract means after the movable contact means has engaged said circuit establishing contact to return said movable contact means to said initial contact.

8. Apparatus for vending a plurality of different priced articles, one at a time, comprising a plurality of coin responsive means for coins of a single unit and of a larger than single unit denominations, and add and subtract means for crediting and debiting units represented by said coins, a plurality of spaced contacts, contact means movable by said add and subtract means from said initial contact to subsequent contacts and then back to said initial contact, a plurality of circuits connected to predetermined spaced contacts, a pair of interlock relays connected in circuits controlled by separate spaced contacts, means for selectively affording energization of at least two of said circuits, each including one interlock relay, depending on the article the vendee desires to purchase, an impulse means responsive to one of said coin responsive means which is operated by a coin of larger denomination than that corresponding to a single unit, means for translating the impulses from said impulse means to said add and subtract means to credit the proper number of units, said add and subtract means also being energized in response to operation of a coin responsive means corresponding to a single unit denomination, a plurality of article delivery means, electrical means for operating one of said article delivery means in response to operation of said coin responsive means when sufficient coins have been inserted to cause said add and subtract means to move said movable contact means a sufficient distance to pass one of said subsequent contacts, engage another thereof and return to said one of said contacts to establish a circuit previously selected, said interlock means including latching means operable upon initial energization thereof, one of said interlock means being initially energized when said movable con-

22

tact means reaches a predetermined contact depending upon the circuit selected, the other of said interlock means being initially energized upon the movable contact means engaging a second contact depending upon the circuit selected after having engaged said predetermined contact and then returned to said second contact, and means for energizing said add and subtract means after said movable contact means has engaged said second contact to return said movable contact means to said initial contact, said interlock relays including two coils, one of which is energized when the movable contact arm reaches a predetermined contact to effect said latching operation, and the other of which is energized when the movable contact means reaches the initial contact to unlatch said latching means.

9. Crediting and debiting apparatus for connection to a source of power comprising an add and a subtract means adapted to be energized from said source of power, a plurality of switches, closure of which operates said add means a different number of times, a plurality of spaced contacts, contact means movable by said add and subtract means from an initial contact to subsequent contacts one of which is passed as the add means operates and then back to said initial contact, means for connecting said contact means to said source of power, a plurality of circuits connected to predetermined spaced contacts, means for selectively affording energization of certain of said circuits depending on the will of the operator, an impulse means responsive to closure of one of said switches which is adapted to operate said add means more than one time, means for translating the impulses from said impulse means to said add and subtract means to credit the proper number of units, one of said switch means being electrically connected to said add means to operate it a single time upon closure of said last mentioned switch, a slow release relay including contacts thereon which are normally closed, means for holding the slow release relay contacts in the open position during the time impulses are being translated to add the proper number of units, a plurality of electrically operated means, means for operating a predetermined one of said operating means when said switches have been operated a predetermined number of times to cause said add means to move said movable contact means a sufficient distance to engage a contact to prepare the circuit previously selected so that when said contact means returns to said passed contact said circuit will be established, said relay contacts being interposed between said subtract means and said source of power, so as to preclude operation thereof during the time that impulses are being transmitted to said add means, and means for energizing said subtract means to return said movable contact means to said initial contact.

10. Crediting and debiting apparatus for connection to a source of power comprising an add and a subtract means adapted to be energized from said source of power, a plurality of switches, closure of which operates said add means a different number of times, a plurality of spaced contacts, contact means movable by said add and subtract means from an initial contact to subsequent contacts and then back to said initial contact, means for connecting said contact means to said source of power, a plurality of circuits connected to predetermined spaced contacts, means for selectively affording energization of certain of said circuits depending on the will of the operator, an

impulse means responsive to closure of one of said switches which is adapted to operate said add means more than one time, means for translating the impulses from said impulse means to said add and subtract means to credit the proper number of units, one of said switch means being electrically connected to said add means to operate it a single time upon closure of said last mentioned switch, a pair of interlock relays connected in circuits controlled by separate spaced contacts, means for selectively affording energization of at least two of said circuits, each including one interlock relay depending on the circuit selected by the operator, a plurality of electrically operated means, means for operating one of said electrically operated means when sufficient credits have been added by said add means to move said movable contact means a sufficient distance to pass one of said separate spaced contacts, engage another thereof and return to said one of said contacts to complete a circuit previously selected, said interlock means including latching means operable upon initial energization thereof, one of said interlock means being initially energized when said movable contact means reaches one of said separate spaced contacts depending upon the circuit selected after having engaged said one of said spaced contacts and then returned to the other of said separate spaced contacts, the other of said interlock means being initially energized upon the movable contact means engaging said one of said separate spaced contacts depending upon the circuit selected, and means for then energizing said subtract means to return said movable contact means to said initial contact.

11. Crediting and debiting apparatus for connection to a source of power comprising an add and a subtract means adapted to be energized from said source of power, a plurality of switches, closure of which operates said add means a different number of times, a plurality of spaced contacts, contact means movable by said add and subtract means from an initial contact to subsequent contacts and then back to said initial contact, means for connecting said contact means to said source of power, a plurality of circuits connected to predetermined spaced contacts, means for selectively affording energization of certain of said circuits depending on the will of the operator, an impulse means responsive to closure of one of said switches which is adapted to operate said add means more than one time, means for translating the impulses from said impulse means to said add and subtract means to credit the proper number of units, one of said switch means being electrically connected to said add means to operate it a single time upon closure of said last mentioned switch, a pair of interlock relays connected in circuits controlled by separate spaced contacts, means for selectively affording energization of at least two of said circuits, each including one interlock relay depending on the circuit selected by the operator, a plurality of electrically operated means, means for operating one of said electrically operated means when sufficient credits have been added by said add means to move said movable contact means a sufficient distance to pass one of said separate spaced contacts, engage another thereof and return to said one of said contacts to complete a circuit previously selected, said interlock means including latching means operable upon initial energization thereof, one of said interlock means being initially energized when said movable contact means reaches one of said separate spaced

contacts depending upon the circuit selected after having engaged said one of said spaced contacts and then return to the other of said separate spaced contacts, the other of said interlock means being initially energized upon the movable contact means engaging said one of said separate spaced contacts depending upon the circuit selected, and means for then energizing said subtract means to return said movable contact means to said initial contact, said interlock relays including two coils, one of which is energized when the movable contact reaches a predetermined contact to effect said latching operation and the other of which is energized when the movable contact means reaches the initial contact to unlatch said latching means.

12. Apparatus for vending a plurality of differently priced articles, one at a time, and making proper change with each article if more than the price thereof is inserted in the apparatus, said apparatus comprising a plurality of coin switch means responsive to coins of different denominations, an add and subtract stepper means for crediting and debiting units represented by said coins in response to operation of said switch means, relay means also operated and maintained thereby during the coin crediting operation, a set of spaced contacts, movable contact means operated by said add stepper means from an initial contact to subsequent contacts and then by said subtract stepper means back to said initial contact, a plurality of pairs of circuits connected to said spaced contacts respectively, means for selectively affording energization of said pairs of circuits depending on the article the vendee desires to purchase, an impulse means responsive to one of said coin switch means which is operated by a coin of larger denomination than that corresponding to a single unit, means for translating the impulses from said impulse means to said add stepper means to credit the proper number of units, a plurality of article delivery means, said relay means energizing said subtract stepper means to return said movable contact means to said initial contact when the add stepper means has credited units corresponding to all of the coins utilized and ceases to maintain said relay means, electrically operated means for operating a predetermined one of said article delivery means incident to selecting a predetermined delivery circuit, and as a result of sufficient coins having been inserted to cause said stepper means to move said movable contact means a sufficient distance to pass a first contact of a circuit previously selected, and engage or pass a second contact and establish a circuit for said subtract stepper through said relay means upon engaging said second contact, and return to said first contact, to establish a delivering circuit previously selected, a single change magazine for holding coins of said single unit denomination, means for delivering the correct change in coins from said magazine by operation of said stepper means incident to said movable contact means having moved past said second contact connected to said preselected energizable circuit and is returning said movable contact means to successively effect engagement thereof with one or more contacts up to and including said second contact connected to said preselected energizable delivery circuit, and means for preventing operation of said change delivery means and said stepper means while said stepper means is crediting units.

13. Apparatus for vending a plurality of different priced articles, or the same priced articles,

one at a time, and delivering the correct change with each article if more than the price thereof is inserted in the apparatus, said apparatus comprising a plurality of coin responsive means for coins of a single unit and of a larger than single unit denominations, an add and subtract means for crediting and debiting units represented by said coins, a set of spaced contacts, contact means adapted to engage successively with said contacts starting from an initial contact, means responsive to movement of said add and subtract means for effecting said engagement, a plurality of circuits connected individually to predetermined contacts, means for selecting the article the vendee desires to purchase, interlock relay means responsive to said contact means engaging the second of said set of spaced contacts as said add means operates and operable to locked position thereby for affording energization of certain predetermined circuits and precluding energization of others until the vending operation is completed, said interlock relay means having unlocking means energized by return and engagement of said contact means with said initial contact for conditioning the apparatus for another vending operation, an impulse means responsive to one of said coin responsive means which is operated by a coin of larger denomination than that corresponding to a single unit, means for translating the impulses from said impulse means to said add and subtract means to credit the proper number of units, said add and subtract means also being energized in response to operation of a coin responsive means corresponding to a single unit denomination, a plurality of article delivery means, electrical means responsive to circuits
